UNITED STATES PATENT OFFICE.

EDWIN E. SLICK, OF WESTMONT BOROUGH, PENNSYLVANIA.

COOLING-BED.

1,076,166.

Specification of Letters Patent.

Patented Oct. 21, 1913.

Application filed March 5, 1913. Serial No. 752,069.

To all whom it may concern:

Be it known that I, EDWIN E. SLICK, a citizen of the United States, residing in the borough of Westmont, in the county of Cambria and State of Pennsylvania, have invented certain new and useful Improvements in Cooling-Beds; and I do hereby declare the following to be a full, clear, and exact description of the invention, such as will enable others skilled in the art to which it appertains to make and use the same.

My invention relates to new and improved construction and form of conveyer, particularly adapted for mechanically handling hot metal bars as they are delivered from a rolling mill and transferring them both longitudinally and transversely as may be desired, and during said transfer to maintain the bars straight and allow the same to cool by the circulation of air or other cooling medium.

My apparatus is especially adapted to receive metal bars of various shapes, such as billets, rounds, squares, flats, I-beams, channels, angles, rails, and is also applicable to any other sections and forms of material, as they are delivered thereto, and by means of my apparatus they may be further guided and transferred longitudinally, then moved laterally singly or in groups, being cooled, if desired, and maintained straight during said transit, after which they are delivered either singly or in groups to the shears or warehouse for storing, loaded directly into cars, or otherwise disposed of, as may be expedient or necessary, and in order to simplify the description, I will refer to such products generally as bars.

Referring now to the accompanying two sheets of drawings which form part of this specification:—Figure 1 is a top plan view of a portion of my improved cooling-bed, with each of its ends broken away for clearness of illustration, the righthand side being substantially complete in details, while the lefthand side of this view shows a portion of my cooling-bed with its shifters, shifter-rods, fulcra and the top guard channel removed to more clearly expose the basis of the structure. Fig. 2 is a vertical transverse sectional elevation taken on the line II—II of Fig. 1, with the exception that all the shifters on both sides of the central line of the cooling-bed are shown in place and in intermediate positions. Fig. 3 is a vertical transverse sectional elevation on an en-

larged scale, as compared with Figs. 1 and 2, of one side of the cooling-bed, and is taken on the line III—III of Fig. 1 showing in full lines the lowest positions of shifters, and in dotted lines the highest positions of the same. Fig. 4 is a longitudinal sectional elevation on a still larger scale, this view being taken on the line IV—IV of Fig. 3, showing two sections of the cooling-bed frame-work and the mechanism for operating the shifters. Fig. 5 is a longitudinal sectional elevation of the portion of the receiving conveyer trough containing the shifter opening in the bottom thereof, showing the inclined portion of the trough for directing the bar therethrough without interference from the edges of the said opening, the arrow indicating the direction of the movement of the bar 19. Fig. 6 shows a number of forms of notches, hollows, serrations, spacers or separators, any of which, or their equivalents, I can use in my apparatus.

This cooling-bed, as shown in Figs. 1 and 2, is adapted to transfer bars laterally in both directions from the central delivery rollers and trough, thereby more fully utilizing the delivery mechanism and space for the purposes desired.

Referring now to the various characters of reference on the drawings:—1 indicates the side base frames, shown in this case as metal castings; 2 is a central base frame of somewhat similar construction; 3 and 4 are the central longitudinal sills shown as angles; and 5 are the longitudinal side sills also shown as angles. The central driving sheaves are indicated at 6, these sheaves being mounted on the same shaft as the flanged receiving rollers 9 which they are adapted to drive.

7 is a cable or belt preferably of wire rope adapted to drive the sheaves 6 and thereby rotate the rollers 9 for the purpose of conveying the bars on said rollers, the bars being guided by the bottom and sides of the receiving trough 10. The cable 7 is driven by any suitable means (not shown) and is guided, and the tension maintained therein by means of the sheaves 8. The receiving trough 10 is provided with openings in the bottom at intervals as shown, through which the end shifters operate to lift the bar from said trough and rollers 9 and deposit it in the adjoining notches of the cooling-bed frame-work 12.

In order that the bars which move longitudinally on the rollers 9 and on the receiving trough 10 shall not be deflected through the openings in said trough, or by 5 the sides of said openings, the bottom of the trough adjoining said openings is provided with downwardly inclined portions as shown at 11 in Fig. 5, which thereby serve as guides to maintain the bar 19 in said trough 10 as it moves therein in the direction of the arrow.

The cooling-bed frame-work is preferably formed in sections as shown, each of said sections being supported on and secured to 15 one of the center sills 3 and the inner side sill 5 and comprising the upwardly extending ribs or plates 12, each of which is provided with a series of notches or serrations 13, which serrations are alined both longitudinally and horizontally, so that a bar lying 20 in the lower apices of a series of adjoined notches will be maintained straight thereby. The portions 12 of the cooling-bed are narrow or comparatively thin laterally, 25 but at the same time deep, thus conduced to strength, while permitting by this construction a free circulation of air or other cooling medium.

Each section of the cooling-rack or frame-work is preferably formed of three plates 12 connected at their ends by the webs 37 and, in order to maintain their shape, they may also be connected together near their intermediate portions by the ribs 38. Each of the 30 sections of the cooling-rack is provided on its exterior with a projecting flange 39 which flanges form supports for the shifter-rods 15, said flanges being recessed or cut away near their central portion as shown at 14 to 35 allow the passage of the downwardly projecting ears or lugs 20 of the shifter-rods. A series or plurality of shifter fingers 17 are pivoted below the notches to the shifter-rods 15 by means of the bolts or rivets 16 and said shifters 17 are adapted to contact 40 their intermediate portions with the fixed fulcra or pins 18 secured in the frame-work 12 for this purpose, as shown.

The bars adapted to be transferred and 45 cooled are indicated at 19 and although these bars are shown in the illustration as being either square or round, they may be of any section or material.

The downwardly depending lugs or ears 50 20 of the shifter-rod 15 are provided with cylindrical holes through which bolts or pins 21 are passed, which pivots one end of the link 22 thereto, the other end of the link being pivoted to the rocker-arm 24 by means 55 of the pin or bolt 23. A main rock shaft 25 is mounted in suitable bearings as shown and is provided with a crank arm 26 secured thereto, to which crank arm a pitman or connecting rod 28 is pivoted by means of

the pin 27. The other end of the said connecting rod or pitman 28 is connected to the crank disk 30 by means of a crank pin 29, the crank 30 being adapted to rotate regularly or intermittently, or to reciprocate, as may be desired, by means of any source of 65 power not shown.

The delivery trough is indicated as 31, which is provided at intervals with delivery conveyer rollers 32 which are driven by the bevel gears 33 which mesh with the corresponding bevel gears 34 mounted on the driving shaft 35, while 36 is a top guard or cover over the driving mechanism shown in this case as a channel.

It should be noted that the interior 80 shifters 17, which adjoin the delivery trough 10, are preferably at a flatter inclination, or lower than the other shifters, when in their lowered positions, this being due to the fact that the fulcra 18 for these shifters are 85 lower than the other fulcra and the end shifter-fingers 17, adjacent to the delivery troughs, are longer than the other shifter-fingers, as shown. The object and effect of this is to permit the end shifters to be lowered 90 below the receiving rollers 9 and receiving troughs 10, as shown in Figs. 2 and 3, this and their extra lengths thereby enabling them to extend the entire width of the trough and contact with the bar 19 during 95 their upward movement, in order to deliver the bar to the first notch of the cooling-bed. The trough 10 having some width, in order to accommodate bars delivered thereto, the distance from the extreme edge 100 of the same to the first notch 13, is greater than that between the succeeding notches, so that the lefthand finger 17 is made longer 105 in order to reach the bar, no matter what position it may have in said trough, and in its extreme lower position the outer end of 110 said finger is preferably lower than the other fingers, in order to provide clearance and insure that it properly contacts with the bar, though the same may be slightly 115 crooked due to deflection when heated. The receiving trough 10 is provided with an upwardly inclined side 40 as shown, to serve as an additional guide in transferring the bar from said trough and rollers 9 to the first 120 notch of the cooling-bed, and the delivery trough 31 is similarly provided with an inclined side 41 to facilitate the delivery of the bars thereto.

The operation of my apparatus is as follows:—Assuming the position of the parts to be as indicated in Fig. 3, hot bars are delivered from the rolling mill in the direction of the arrows shown in Fig. 1, and after the last end of a bar has reached the cooling-bed, the crank 30 is caused to revolve, thereby rocking the shaft 25 by means of the crank arms 26 and the connections as shown,

which rocking of the said shaft causes a corresponding movement of the rocker arm 24, which thus gradually slides the shifter-rods 15 on the supporting angles 39. The shifters 17 being pivoted at their lower ends to the shifter-rod 15, their lower ends move forward with said bar, while their intermediate portions contact with and slide on the fulcra 18, these shifters thus forming levers 10 of the first class, with the addition of the sliding motion as stated. The upper and outer portions of the end shifters 17 then contact with the lower surface of the bar 19 on the receiving rollers and in the trough 15 and by a continuation of the movement just described, the bar is deposited in the first notch of the cooling-table as shown. When the shifters 17 are in their lowered positions, the first part of the movement of the 20 shifter-rod 15 causes them to move bodily, but without much lifting or rocking movement, and this is due to their comparatively small inclination from the line of movement of the shifter-rod and the relative positions 25 of the pivots 16 and the fulcra 18. This movement therefore, causes the upper ends of the shifters 17 to be introduced below the bars 19 and insures this action, after which the continuation of the movement of 30 the shifter-rod causes the shifters to rock in increasing degrees, thereby accomplishing the purpose intended. It should also be noted that during the movement of the shifters they rock and slide on the fulcra 35 in varying relative amounts, dependent on the degrees of their angularity with respect to the line of movement of their pivots. The curves through which the upper ends of the shifters rock are secondary conchoids as indicated at 42 and 43 of Fig. 3, and the shifters are thus peculiarly adapted to operate in the manner desired. If a bar is in one of the series of notches of the cooling-table, the corresponding shifters will traverse it laterally into the next series of 40 notches and this will occur at each revolution or reciprocation of the crank 30. During the transverse travel of the bars from one series of notches to the next series, they are maintained straight by the alinement of 45 said notches, and are gradually and properly cooled by the circulation of air or other cooling medium, which circulation is permitted by the open construction of the cooling rack or frame-work 12. After having 50 passed over the cooling-bed, as shown, the bar is deposited on the delivery rollers 32 and in the delivery trough 31, whereby it may be transported to a shears, storehouse, loading-platform, and thence to cars, or otherwise as may be desired.

From the foregoing it will be understood that my cooling-bed and apparatus is so arranged and adapted that it will take bars from rolling mills and mechanically trans-

fer them to a shears or elsewhere, the bars being cooled as they pass across the bed and also maintained straight during this transfer.

Although in the drawings forming part of 70 this specification, my cooling-bed is shown as horizontal, I wish it understood that it may also be inclined either upwardly or downwardly, as desired.

The receiving trough of my apparatus is 75 comparatively narrow and provided with sides and the receiving rollers are similarly narrow and provided with flanges at the end of same, all for the purpose of maintaining the bars straight as they are delivered 80 from the rolls, and the frictional contact of the receiving rollers 9 on the lower surface of the bars serves to transfer them longitudinally without buckling or kinking, as might be the case where no rollers are provided. I also wish it understood that the supporting racks of my cooling-beds may be spaced nearer together or farther apart, as 85 may be desired or necessary to accommodate bars of different diameters, sections or temperature, and the apparatus is adapted to 90 operate upon bars of any lengths. It should also be noted that the shifters of my apparatus are spaced close enough together so 95 that they pick up a hot bar without buckling and they are also adapted to pick up and transfer bars from the delivery rolls to the notches of the receiving table, even though the bar should be moving, and the frictional contact of the bar with each 100 shifter serves as a brake to stop it gradually without deformation.

The notches or hollows formed integrally in the bar 12 may be made of any of the shapes illustrated on the left-hand portion 105 of Fig. 6, and I also may use removable spacers or separators made and arranged in any of the forms illustrated on the right-hand portion of Fig. 6. The forms of separators shown on the righthand portion of Fig. 6 can be made so that they can be removed and replaced when necessary on account of wear or breakage. Alternate ones 110 may also be omitted or removed to give greater distances, longitudinally of the supports, between the hollows or notches formed thereby, in order to accommodate bars of different sizes or shapes, but to do this the shifter levers 17 and the amplitude of their rocking should be adjusted, as will be readily 115 understood.

Although I have shown and described my improvements in considerable detail, I do not wish to be limited to the exact and specific details shown and described, but may use 120 such substitutions, modifications or equivalents thereof, as are embraced within the scope of my invention, as pointed out in the claims.

Having thus described my invention, what 130

I claim and desire to secure by Letters Patent is:—

1. In a cooling-bed, a plurality of stationary supports provided with a series of alined notches in the upper surfaces thereof, a corresponding series of shifters pivoted at their ends, and means for rocking and sliding said shifters, whereby a bar is advanced step by step on and over said bed.
- 10 2. In a cooling-bed, a plurality of parallel stationary supports provided with alined notches in the upper surfaces thereof, a series of shifter levers pivoted below said notches, and means for rocking said levers, whereby a bar is laterally advanced across said bed step by step.
- 15 3. In a cooling-bed, a plurality of stationary supports, provided with alined notches in the upper surfaces thereof, a series of shifter levers pivoted below and corresponding to said notches, a plurality of shifter-rods to which said shifter levers are pivoted, a fulcrum between each pivot and the extremity of the corresponding lever, and means for reciprocating said shifter-rods.
- 20 4. In a cooling-bed, a series of narrow stationary supports spaced apart and provided with alined notches in the upper edges thereof, a series of shifter levers pivoted below said notches, and means for simultaneously rocking said levers, whereby a bar is laterally advanced across said bed step by step.
- 25 5. In a cooling-bed, a series of narrow stationary supports spaced apart and provided with alined notches in the upper edges thereof, a plurality of shifter levers pivoted below said notches, a series of shifter rods, reciprocably supported below said notches, to which said shifter levers are pivoted, a fulcrum between each pivot and the other extremity of the lever, and means for reciprocating said shifter-rods.
- 30 6. In a cooling-bed, a series of stationary supports each comprising a plurality of plates spaced apart with one of each of their edges projecting upwardly, a series of alined notches in said upper edges, a series of shifter levers provided with and pivoted to a reciprocable shifter-rod below said notches, a fulcrum between each pivot and the other extremity of each shifter lever, and means for reciprocating said shifter-rod.
- 35 7. In a cooling-bed, a plurality of stationary supports provided with alined notches in the upper surfaces thereof, a series of 55 sets of shifter levers normally in inclined position below said notches, a shifter-rod pivoted to the lower ends of each of a set of shifter levers, fixed fulcra located between the pivots and the other ends of the shifter levers and adjacent to an intermediate portion thereof, and means for reciprocating said shifter-rod.
- 40 8. In a cooling-bed, a series of stationary supports, each comprising a plurality of 65 plates spaced apart with one edge of each projecting upwardly and provided with a series of alined notches therein, and flanges projecting laterally from the lower portion of a pair of adjacent supports adapted to 70 slidably hold a shifter-rod thereon.
- 45 9. A cooling-bed comprising a series of stationary supports, each comprising a plurality of plates set on edge, spaced apart and secured together at their ends, the upper edges of said plates being provided with a series of alined notches formed therein, laterally projecting flanges on the lower portions of a pair of adjacent supports, shifter-rods slidably mounted on said flanges 80 and provided with depending lugs, said flanges being provided with recesses through which the ears of said shifter-rods project.
- 50 10. In a cooling-bed, a plurality of stationary supports, provided with a series of 85 alined hollows formed in the upper surfaces thereof, a series of shifter levers pivoted below said hollows, and means for rocking said levers, whereby a bar is laterally advanced across said bed, step by step.
- 55 11. In a cooling-bed, a plurality of stationary supports, a plurality of spacers mounted thereon, thereby providing a series of alined hollows on the upper portions of said supports, a series of shifter levers pivoted below said hollows, and means for rocking said levers, whereby bars are laterally advanced across said bed, step by step.
- 60 In testimony whereof I hereto affix my signature in the presence of two witnesses. 100
- EDWIN E. SLICK.
- Witnesses:
